UNITED STATES PATENT OFFICE.

JOHN GRIESMAIER, OF CHICAGO, ILLINOIS.

LOCKER.

1,134,330.

Specification of Letters Patent.

Patented Apr. 6, 1915.

Application filed August 10, 1914. Serial No. 856,063.

To all whom it may concern:

Be it known that I, JOHN GRIESMAIER, a citizen of the United States, residing at Chicago, in the county of Cook and State of Illinois, have invented certain new and useful Improvements in Lockers, of which the following is a specification.

The locker which is the subject matter of the present application for patent is designed more particularly for use in hotels, 10 restaurants, barber shops and similar places, its object being to provide a safe place for the customer's wraps, hat, umbrella, etc.

The invention also has for its object to provide a novel and improved coin or check-controlled lock for the locker.

In order that the invention may be better understood, reference is had to the accompanying drawings, in which—

Figure 1 is a perspective view of the locker; Fig. 2 is an enlarged vertical section thereof; Figs. 3 and 4 are elevations of the doors forming the closure of the locker; Fig. 5 is an elevation, partly in section, 25 showing the lock; Fig. 6 is a view similar to the preceding, showing the parts in another position; Fig. 7 is a horizontal section on the line 7—7 of Fig. 5; Fig. 8 is a horizontal section on the line 8—8 of Fig. 30 6; Fig. 9 is a face view of the coin or check-controlling means of the lock, and Fig. 10 is a perspective view of a portion of the lock housing.

Referring specifically to the drawings, the locker is a tall box-like structure having sides 12, a back 13, a top 14 and a bottom 15. The front wall of the locker comprises top and bottom sections 16 and 17, respectively, 40 which are spaced to provide an opening through which access is had to the interior of the locker. This opening is provided with a closure comprising two sliding doors 18 and 19, respectively. In the locker, a short 45 distance above the bottom 15, is a false bottom 20, beneath which is located a shallow pan or drawer 21, slideable into or out of the locker through an opening in the bottom front wall section 17. The false bottom 50 has perforations 22, and its purpose is to support an umbrella, the latter being stuck into one of the perforations 22. If the umbrella is wet, the drippings will be caught in the pan 21.

The doors 18 and 19 are screened as shown in Figs. 1 to 4, and they slide, one in

front of the other, in grooves 23 formed by strips on the side walls 12, said grooves being separated by a parting strip 24. On the inner face of the top and bottom rails of 60 the lower door 19 are longitudinal ribs 25, and on the outer face of the top and bottom rails of the top door are longitudinal ribs 26. When the two doors are slid upward to closing position, the top rib 25 and the 65 bottom rib 26 meet, and if the upper door 18 is locked, the lower door is held by the ribs from being slid downward to open position. All the ribs, except the bottom rib of the lower door stop short of the side edges 70 of the doors so that they may clear the parting strips 24, and said bottom rib serves to prevent the lower door from being slid upward after it reaches its closing position, said rib being then in contact with the bottom 75 of the parting strips, the latter therefore serving as stops to limit the upward travel of the lower door. The parting strips do not extend down to the bottom of the door way but stop a sufficient distance thereabove, so that when the doors are slid downward to open position, they seat below the parting strips as shown in Fig. 2. In order to cushion the doors when they are slid down to open position, a rubber or other 80 cushion 27 is mounted at the bottom of the door way.

The locker will be provided with suitable garment hangers, as shown in Fig. 2.

The following check or coin-controlled 90 locking mechanism is provided: On the outer face of the top section 16 of the front wall of the locker, over an opening in said section, is mounted a plate 28, on the back of which, and consequently on the inside of 95 the locker, is a coin chute formed by laterally spaced, parallel vertical ribs 29 and a cover plate 30 extending across the latter. The ribs form the side walls of the coin chute and their upper ends, where the coin 100 or check is inserted, are flared as shown at 31 and project from the top 14 of the locker. In the entrance end of the coin chute are mounted two opposed bowed springs 32 which accelerate the drop of the coin or 105 check. The springs spread as the coin or check is inserted, and when the latter is forced past the springs, they draw together and snap the coin or check down the chute. At the bottom of the coin chute is an inclined shelf 33 which deflects the coin or 110 check into a receptacle 34 hinged at its rear

end, at 35, in an opening in a horizontal partition 36 mounted in the upper portion of the locker, and cutting off this part of the locker from the other part in which the garments, etc., are placed. A suitable lock 37 is provided for holding the receptacle up. Upon unlocking the receptacle and tilting it down, as shown dotted in Fig. 2, and opening the doors 18 and 19, access may be had to the coins or checks in the receptacle.

In the plate 28 is a key hole or slot 38, and below the latter the plate has an aperture 39 for a bolt 40 carrying a chain 41 which is connected to the upper door 18 and is of such length that when said door is closed and the bolt is in place and locked, said door cannot be slid down to open position. The opening of the lower door 19 is prevented by the means hereinbefore described.

On the back of the plate 28, to one side of the coin chute, is mounted a vertical slide 42 comprising a flat plate held in place between undercut guide ribs 43 on the plate 28. The slide has a vertical slot 44 divided by a cross bar 45 into upper and lower sections, the top of the former being reduced in width, as indicated at 46. The upper slot section registers with the key hole 38, and the lower slot section registers with the aperture 39. The lower end of the slide reduces to a narrow strip 47 having an outstanding flange 48.

To the back of the plate 28 is pivoted a lever, one end 50 of which is below and in line with the coin chute so as to intercept the check or coin falling down the chute. This end of the lever is widened so that the check or coin may not miss the same. The other end 51 of the lever is positioned so that it is in contact with the flange 48. The end 50 is normally positioned across the lower end of the coin chute. A check or coin dropping down the chute, upon striking the end 50, tilts the lever, so that the end 51 swings upward, and as said end engages the flange 48, the slide 42 is carried upward. As the coin clears the lever, it drops on the shelf 33 and is deflected into the receptacle 34.

Against the back of the plate 28 is mounted a housing which incloses and supports the remaining parts of the lock which will now be described. This housing comprises two laterally spaced vertical plates 52 and 53, respectively, having at their rear vertical edges outstanding flanges 54 which are bolted or otherwise secured to a supporting arm 55 carried by the back 13 of the locker. The forward vertical edge of the plate 52 abuts against the back of the plate 28 over the slide 42, said edge having a recess 56 to accommodate the slide.

On the plate 52 are mounted two vertically spaced, horizontal guide strips 57, the

space between the same being in alignment with the key hole 38. To the rear of these guide strips is mounted a series of main tumblers, which are angular, each tumbler comprising two arms 58 and 59, respectively. The tumblers are pivotally mounted, side by side, on a pin or stud 60 carried by the plate 52. The arms 58 of the tumblers point upward, and the arms 59 are horizontal and point toward the slide 42. The upper end of the arms 58 are in line with the space between the guide strips 57 so that they may be engaged by the key 61, said ends being reduced to different widths and the inner end of the key being correspondingly shaped as shown at 62, in Fig. 8. Thus a special key, corresponding to the arrangement of tumblers, or the combination, is necessary. The proper key, when inserted through the key hole 38 and pushed against the upper ends of the tumbler arms 58, will swing the latter as one on the pivot 60. The strips 57 guide the key to the tumblers.

The tumbler arms 59 have bottom hooks 63 at their forward ends to engage an abutment 64 on the inner end of the bolt 40 and thus prevent withdrawal of the latter. However, when the tumblers are operated to disengage the hooks from the abutment, the bolt may be withdrawn and the door 18 is then free to be slid down to open position. The plate 53 carries a guide 65 for the bolt.

Above the arms 59 of the main tumblers is mounted a series of auxiliary tumblers 66, which are substantially U-shaped, the two branches pointing downward. These auxiliary tumblers are pivotally mounted at the connecting portion of their branches on a pin or stud 67 carried by the plate 52. The rear branches seat on the top edges of the branches 59 of the main tumblers, said edges being slightly recessed to form a seat, as shown at 68. The forward branches of the auxiliary tumblers terminate in a forwardly extending finger 69 designed to enter the slot 44 to engage the bottom of the cross bar 45 and hold the slide 42 elevated. When the fingers 69 are withdrawn from the cross bar, the slide is released so that it may drop by gravity.

The function of the slide 42 is to prevent withdrawal of the key 61 after it is inserted in the lock. The shank of the key, adjacent to its bow or handle has a reduced neck portion 70 forming transverse notches in opposite edges of the shank. The opposite side walls of the reduced upper end 46 of the slot 44 are designed to seat in these notches, and when thus seated the key cannot be withdrawn.

Proper return springs 71 for the main and auxiliary tumblers are provided. The main tumblers swing between stop lugs 72 on the plate 52.

On the plate 53 is an outstanding hori-

5 horizontal rib 73 positioned to seat in a longitudinal side slot 74 in the bolt 40 when the latter is inserted into the lock. Thus, the bolt can only be inserted one way, which is sure to be the proper way. The bolt also has a bottom rib 75 to take a reduced bottom portion 76 of the aperture 39, which prevents lateral motion of the bolt which might injure the main tumblers.

10 A pin 77 carried by the plate 28 and extending into the slot 44 serves as a stop to prevent the slide from dropping down too far.

The key hole 38 has a reduced bottom portion 78 which acts in conjunction with a lug 79 on the under side of the key 61 to insure the proper insertion of the key.

The operation of the lock may be summarized as follows: When the bolt 40 is out of the lock, the door 18 is free to be slid down to gain access to the locker. The coin actuated lever 50, 51 is normally in the dotted line position shown in Fig. 9, the slide 42 being down and the part 46 of the slot 44 locking the key 61 in the key hole 38. The last previous insertion of the key operated the main and auxiliary tumblers and placed the same in the position shown in Fig. 6, the main tumblers having been swung to release the bolt, and the auxiliary tumblers having been swung to release the slide so that it was free to drop down to lock the key. The lock is now inoperative as the key cannot be removed. If a person now wishes to use the locker, and after placing the garment, hat, etc., therein, he drops a coin or check of the required denomination into the coin chute, and after raising the doors 18 and 19, the bolt is inserted. As the coin or check drops down the chute and strikes the part 50 of the lever, the slide 42 is pushed upward to release the key, and the bolt is locked by the hooks 63 of the main tumblers. The fingers 69 of the auxiliary tumblers also come under the cross bar to lock the slide against downward movement. The bolt is now locked, and the key may be removed and kept by the person using the locker until said person wants to remove the garment, hat, etc., the parts being in the position shown in Fig. 5. To unlock the bolt, the key is inserted to operate the main tumblers, whereupon the parts again assume the position shown in Fig. 6, and the bolt is unlocked, the key being again locked as hereinbefore described. The bolt being unlocked, it may be withdrawn to open the locker doors, and the parts are now ready for the next person desiring to use the locker.

60 It will be seen from the foregoing that

the locker doors cannot be locked without inserting a coin or check. If a key is lost or stolen, the lock can be opened to change the combination and a new key supplied, thus rendering the original key useless. 65

I claim:

1. A lock comprising a housing, a key and a bolt insertible into the housing, key-operated main tumblers for locking the bolt against withdrawal, a slide having means 70 for locking the key against withdrawal, the key when thus locked holding the main tumblers inoperative, check-controlled means for actuating the slide to release the key, and auxiliary tumblers for holding the slide in 75 inoperative position when the bolt is locked, said auxiliary tumblers being operated by the main tumblers.

2. A lock comprising a housing, a key and a bolt insertible into the housing, key-operated tumblers for locking the bolt against withdrawal, a slide having means for locking the key against withdrawal, the key when thus locked holding the tumblers inoperative, check-controlled means for actuating the slide to release the key, and means 80 actuated by the tumblers for holding the slide in inoperative position when the bolt is locked.

3. A lock comprising a housing, a key and a bolt insertible into the housing, key-operated pivoted main tumblers for locking the bolt against withdrawal, a slide having means for locking the key against withdrawal, the key when thus locked holding 90 the main tumblers inoperative, check-controlled means for actuating the slide to release the key, and pivoted auxiliary tumblers for holding the slide in inoperative position when the bolt is locked, the main tumblers having parts engageable with the auxiliary tumblers for actuating the same. 95

4. A lock comprising a housing, a key, a bolt having a longitudinal side slot, said key and bolt being insertible into the housing, 105 a rib in the housing which enters the bolt slot when the bolt is inserted into the housing, key-operated tumblers for locking the bolt against withdrawal, means for locking the key against withdrawal, the key when thus locked holding the tumblers inoperative, and check-controlled means for actuating said key-holding means to release the key. 110

In testimony whereof I affix my signature 115 in presence of two witnesses.

JOHN GRIESMAIER.
